UNITED STATES PATENT OFFICE.

JOHN W. BAILEY, OF DENVER, COLORADO.

ORE PULVERIZING AND AMALGAMATING MILL.

SPECIFICATION forming part of Letters Patent No. 530,612, dated December 11, 1894.

Application filed March 1, 1894. Serial No. 501,938. (No model.)

To all whom it may concern:

Be it known that I, JOHN W. BAILEY, of Denver, in the county of Arapahoe and State of Colorado, have invented certain new and useful Improvements in Ore Pulverizing and Amalgamating Mills, whereof the following is a specification, reference being had to the accompanying drawings.

My invention consists of an ore pulverizer, 10 in combination with an electric amalgamator, which is so arranged that the space between the crushing surfaces where the pulverization is continuously taking place is within a field of electrical action set up between a 15 metal or carbon plate constituting an anode on one side of the crusher and a trough containing mercury constituting the cathode upon the opposite side.

The object of my invention is to provide 20 means whereby the process of amalgamation may occur at the very instant that the gold or other metal is liberated from the ore within which it is embedded, and before it has become in the slightest degree contaminated by 25 other substances which are invariably mingled with the ore from the mine.

The application of electricity to the process of amalgamation has already overcome many of the difficulties heretofore experienced by reason of the deleterious action upon the mercury of arsenic, sulphur, and various organic substances, especially oil, which are almost always present in the stock which is presented to the action of the amalgamator; but though the electrical action tends to keep the mercury clean and bright so as to hasten the amalgamating process, difficulty is often experienced by reason of the oil or grease or other organic substance 35 mingled with the ore becoming mixed with the gold or other metal. If the gold is coated with oil or grease the process of amalgamation does not proceed, no matter how clean the surface of the mercury may be kept. In 40 order to reach this difficulty I have provided a device whereby the pulverizing of the ore takes place directly over the trough of mercury and within a field of electrical action. The anode therefore draws to itself 45 all organic substances, while the gold or other metal at the very moment of its birth, and before there is an opportunity for contami-

nation, passes to the mercury. A further advantage of this arrangement is that exceedingly minute particles of metal, which owing to their fineness have in any other process to which the stock may be subjected a tendency to float and consequently to avoid a mercury surface over which the stock may be passed, are here, by reason of the violent 60 commotion of the grinding process, brought into contact with the mercury.

I have illustrated my invention as applied to a type of pulverizer invented by me, and for which I obtained Letters Patent of the 65 United States, No. 321,937, dated July 14, 1885, but it is to be understood that it is equally applicable to pulverizers of different sorts.

In the accompanying drawings Figure 1 is a vertical section of my improved device. 70 Fig. 2 shows certain details of connection for the driving mechanism; and Fig. 3 shows the relative positions of the anode and cathode, the entire pulverizing machine being removed.

A is the containing vessel or pan, strongly constructed of metal and suitably supported.

B is a heavy disk or muller, revolving rapidly within the pan.

The crushing and wearing surfaces, both of 80 the pan and of the muller, are reinforced by removable grinding surfaces or hard iron or steel. Of these a is a vertical ring, which forms the inner grinding surface of the pan. It is surrounded by another concentric ring, 85 a', held in place by wedges, a².

b is a ring and annular disk which forms the outer and lower surfaces of the muller. Opposite this lower surface of the muller there is a corresponding removable disk, a³, 90 affixed to the bottom of the pan A. When any of these removable surfaces are worn out they may be replaced by new ones.

The outer diameter of the muller with its crushing surface is somewhat less than the 95 inner diameter of the corresponding crushing surface of the pan.

C is a vertical shaft, situated beneath the muller and to which it imparts its motion. It is driven by the bevel gear, c, and passes 100 through a stuffing box, c', in the bottom of the pan. Upon the upper end of the shaft, C, and immediately beneath the muller, there is affixed an enlarged head, E, bolted to the

shaft and revolving with it. This head has a large flat surface at its upper end presented toward the lower surface of the muller.

Projecting from the lower surface of the 5 muller at its center is a stout pin, D, carrying at its lower end a square brass box, d. This box is received into a slot, F, running across the upper surface of the head, E. A strong 10 spring, f, interposed between the end of the slot and the box, d, tends to drive the box, and with it the center of the muller, along the slot away from the center of the shaft, C. This renders the muller slightly eccentric to the shaft.

15 G is the water feed pipe. It enters the bottom of the pan through an annular space, g', surrounding the shaft, C, just above the stuffing box, c'. From this, part of the water passes directly up around the shaft into the 20 larger water space, g², formed in the bottom of the pan around its center. Another part of it passes, by means of a passage, g³, running from the annular space, g', up through the center of the shaft, C, into the slot, F, 25 and thence over the top of the head, E, into the water space, g². The object of this distribution of the water is to keep the wearing surfaces of the shaft and surrounding parts free from grit which might otherwise pass 30 down from the pan. The water enters around and above the shaft at high pressure, carrying any grit or dirt up with it. From the space, g², the water passes by means of pipes, h, h, directly through the muller and into the 35 pulverizing part of the mill. These pipes have their heads turned over to prevent larger pieces of ore from falling down them.

H is the discharging pipe near the top of the pan, through which the water escapes.

40 I is the chute by which the ore is fed into the pan.

J is a draw-off pipe to be used when cleaning up.

45 The operation of this portion of my device is as follows: The ore is fed into the pan by the chute, I, and falls on the revolving muller, the rotation of which tends to throw it toward the crushing surfaces at the edge. The shaft, C, being driven rapidly imparts to the 50 muller an eccentric or rolling motion, the degree of eccentricity depending upon the extent to which centrifugal force combined with the action of the spring, f, overcomes the resistance of the material to be pulverized.

55 At the same time the muller being free to revolve upon its own axis within the box, d, the contact of its periphery with the pan imparts a rotatory motion which allows the crushing to be accomplished with less friction than 60 would otherwise be the case. A continuous stream of water is fed into the lower part of the pan through the tube, G, water space, g', and tubes, h, h. The water rises carrying with it the finely pulverized gangue, and 65 passes off through the discharge pipe, H. The fineness to which the pulverizing process is carried may be varied at will by con-

trolling the rate of the in-flow of water by the cock, g. If the in-flow is comparatively slow the ore will be ground very fine before 70 being carried off by the water through the discharge. If rapid, it will be carried off before it is ground so fine.

I have thus far described the construction and operation of the pulverizing apparatus 75 which as before stated belongs to the same type of machine as a device previously patented by me. I will now describe the application to this device of the electric amalgamating apparatus.

80 Immediately over the annular space between the crushing surfaces, there is suspended a large copper ring, N, corresponding in diameter to this annular space and insulated from the pan, A. This ring is electrically connected with the positive pole of a suitable source of electric supply and constitutes the anode of my electric amalgamator. Immediately below this same annular space and contained within a circular trough, or groove, 85 k, hollowed out in the bottom of the pan, A, is a ring of mercury, K, connected electrically with the negative pole of the source of electric supply, and constituting the corresponding cathode. The mercury is properly insulated from the pan, A, by means of a lining, k', of hard rubber or other non-conducting material inserted in the trough which contains the mercury. M is a tap for drawing off the mercury from the trough, k, and refilling the 90 same. The space between the anode and the cathode being filled with water containing in suspension powdered ore of all degrees of fineness, electrolytic action is at once set up driving any organic substances up to the anode 95 and metallic particles down to the mercury cathode where amalgamation takes place. This action takes place continuously and consequently seizes upon the free metal the instant it is liberated in the crushing process. 100 It is to be noticed particularly that neither of the crushing surfaces has any electric connection. This would prevent what is my main object, viz: to effect the crushing between the two poles of an electric amalgamator. Consequently both the anode and cathode are 105 completely insulated from the entire pulverizing apparatus. Their relative position is seen in Fig. 3. Between these, and electrically disconnected from them but within the 110 sphere of their electric activity, is the space between the crushing surfaces.

I am aware that hitherto attempts have been made to set up electric action of this description in the immediate vicinity of the 115 crushing surfaces of an ore crusher; but in every case one or both of the crushing surfaces have themselves been so connected as to act as anode or cathode, instead of being completely insulated from either. Consequently these devices have entirely failed to attain what it is my chief object to attain, namely: an electric amalgamator with crushing surfaces between and within the sphere 120

of, but electrically disconnected from the poles of the amalgamator.

Although I have thus illustrated my invention as it is applied to a pulverizing machine 5 of the type shown by me in the drawings accompanying this specification, which I find a convenient form for its application, yet it is obvious that it is applicable to crushing machines of a different nature and construction. 10 Whatever may be the shape of the crushing surfaces and consequently the shape of the space within which the crushing action takes place, an insulated trough filled with mercury may be placed immediately below this 15 crushing space, and a corresponding metallic plate may be similarly placed above it. The mercury and plate may be electrically connected with a source of electric supply, constituting an anode and cathode from which 20 the crushing surfaces are electrically disconnected.

Having thus described my invention, I claim—

1. In an ore pulverizing and amalgamating 25 device, the combination of opposing crushing surfaces whereby the ore is pulverized and an amalgamating device consisting of a metal plate, and a mercury trough, situated each

on opposite sides of the space between the crushing surfaces, and electrically connected 30 so as to form respectively anode and cathode, substantially as described.

2. In an ore pulverizing and amalgamating device, the combination of opposing crushing surfaces whereby the ore is pulverized, and 35 an amalgamating device consisting of suitable electrodes, insulated from each other and from the crushing surfaces, and so situated that the entire space within which the crushing takes place is within the sphere of 40 the electrical action between the electrodes, substantially as described.

3. In an ore pulverizing and amalgamating device, a cylindrical pan, a cylindrical muller, means for rotating said muller within said 45 pan, an annular insulated trough filled with mercury situated below the periphery of the muller, an annular insulated metal plate situated above the periphery, and suitable electric connections whereby the metal plate becomes 50 an anode and the mercury a cathode, substantially as described.

JOHN W. BAILEY.
